UNITED STATES PATENT OFFICE

ALLAN J. CLINE, OF CHICAGO, ILLINOIS

WEB TENSION DEVICE

Application filed March 31, 1930. Serial No. 440,230.

This invention relates to web tension apparatus for controlling the rotation of web rolls such, for example, as the paper rolls used to supply printing presses, such rolls being ordinarily supported by roll stands or reels located underneath the presses, as in the basement or on a lower floor of the printing plant.

Tension mechanism of this general character to which my invention is particularly adaptable is shown in Scott Patent No. 1,610,713, it being an object of the invention to provide means whereby tension mechanism, such as is shown in this patent, may be adjusted and the tension thereby controlled from a remote point, as from a pressroom control station, whereby the pressmen may vary the tension on the web from time to time, in accordance with changing conditions, without the necessity of calling down to the roll tenders in the basement or otherwise signalling for an adjustment of the tension.

The invention is also applicable to tension mechanism such as that shown in my pending application, Serial No. 389,363 and other adaptations of it will be readily apparent.

Referring to the drawings:

Fig. 1 is a side elevation of a roll stand equipped with tension mechanism in which my invention is embodied, one of the pedestals of the roll stand being removed and the printing machine being diagrammatically illustrated;

Fig. 2 is a side elevation of the movable collar and associated parts by which the brake mechanism is actuated; and

Fig. 3 is an elevational and sectional view showing the device of the invention applied to the tension mechanism shown in my co-pending application above mentioned.

In the embodiment of the invention shown in Fig. 1, the reference character 11 indicates a press unit (shown diagrammatically) adapted to be supplied with paper from web rolls 12 supported in the basement or upon a sub-level, said rolls being carried by a roll stand comprising spaced pedestals 13 in the upper ends of which is journaled a shaft 14 which carries two spiders 15 located at the opposite ends thereof and provided with

spindles 16 adapted to support the rolls 12, this part of the construction being well known in the art. The web 17, which is shown in two positions to indicate the full and depleted condition of the roll passes over a floating or spring roller 18, thence downwardly around a compensating roller 19 from which it is directed upwardly through the pressroom floor 21 and over a guide roller 22 forming a part of the press mechanism. The roller 18 is mounted in a bracket 23 and is normally urged upwardly by means of a spring 24 mounted on a rod 25 connected with a bearing block 26 in which the end of the roller is carried, it being understood that this mechanism is duplicated at the opposite end of the roller so that the latter will be properly balanced. The mounting of the roller 19 will be later described.

The shaft 14, carrying the spiders 15 between which the rolls are supported, is adapted to be rotated in any suitable manner as by means of a motor (not shown) which is connected to drive a large spur gear 27 mounted on said shaft 14.

The spindles 16 are provided with friction wheels 28 adapted to be clamped by straps 29 and 31 which are connected at their outer ends by means of a hand screw 32 and at their opposite ends by means of a toggle 33, so that they may be tightened upon said friction wheels 28 to provide the desired tension thereon, said straps thus serving as brakes, which, as will presently appear, may be automatically tightened when the web is slack and loosened when it is taut.

The toggles 33 are each provided with a rod 34 extending inwardly toward the shaft 14, being supported in brackets 35 on the spiders 15. Said rod 34 is equipped at its inner end with a screw 36 adapted to engage a cam surface 37 on a collar 38 slidably mounted upon the shaft 14, said collar being held against rotation by means of a pin 39 which is adapted to extend into a socket in the pedestal 13. Said collar 38 is provided with a groove 41 in which there is disposed a yoke 42 connected by means of a link 43 with a rod 44 extending upwardly and connected at its upper end with a lever 45 which is pivoted

at 46 to a frame bracket 47. Said lever 45 extends beyond the pivot 46 and the opposite end 48 thereof is connected by means of a spring 49 with a fixed part on the frame, the upper part of said spring and its connection to the frame being omitted for convenience in illustration.

The roller 19, previously mentioned, is carried by arms 51 mounted upon a shaft 52, said arms being extended beyond said shaft and the opposite ends 53 thereof being connected by means of a rod 54 to a dashpot 55 which serves to steady the roller 19 and to prevent undue vibration thereof.

18 The shaft 52 also carries an arm 56 which is provided with a roller 57 bearing upon the arm 48 of the lever 45. The movement of the roller 19 is thus transmitted to the lever 45 and, by means of the rod 44, to the yoke 42 which actuates the collar 38 thereby actuating the toggle to the brake 29, 31 on the active roll i. e., the roll now shown at the right in Fig. 1. It will be evident that when the roller 19 is raised by reason of increased tension on the web, due to increased speed of the press or to other causes, the rod 44 will be lowered, causing the collar 38 to be moved to the left viewing Fig. 2, thereby loosening the straps 29 and 31 on the friction wheel 28 and when the roller 19 is permitted to lower by reason of slack in the web the effect upon the brake will be the opposite to that just described causing the straps 29 and 31 to be tightened upon the friction wheel 28 thereby slowing down the roll.

A threaded rod 58 is supported on the shaft 52 and extends in opposite direction to the arms 51, said rod 58 being provided with a counterweight 59 which, in accordance with 40 the present invention, consists of a small motor which is adapted to be moved along said rod 58 by its own power to thereby adjust the weight according to changing conditions in the operation of the press, said 45 motor being subject to control by the pressmen on the floor above by means of a reversing switch diagrammatically illustrated at 61. Said switch is connected to an electric line, the opposite sides of which are indicated by the reference numerals 62 and 63, and may be of any standard type whereby 50 the direction of flow of the current through the motor may be reversed at will, said switch being connected with the motor by suitable wiring contained in a cable 64. The 55 details of the mounting of the motor 59 are best shown in Fig. 3, from which it will be noted that the motor shell is suspended from a bracket 64 carried upon a hub part 65 of a gear 66 which meshes with a pinion 67 on the armature shaft, said hub portion 65 being threaded upon the rod 58 so that rotation of said gear 66 moves the entire assembly lengthwise of the rod. By thus providing 60 for the control of the counterweight from

the pressroom floor, the tension on the roll may be varied at will by the pressmen who are in best position to judge the needs for change in the tautness of the web and it is rendered unnecessary for the pressmen to 70 call to, or otherwise communicate with, the men in the basement when a tension change is desired.

The same adjusting means may be applied to a tension device of the type shown in my 75 prior application, Serial No. 389,363, hereinabove mentioned, this adaptation of the invention being illustrated in Fig. 3. In said figure a tension strap 68 is shown as secured at its lower end to a spring bolt 69 mounted 80 in an angle member 71 permanently attached to the floor, said strap extending from said bolt around a roller 72, thence upwardly in contact with the surface of the roll (which is shown as full in the dotted line position and as partially depleted in the solid line position), the upper end of the strap being connected to an arm 73 carried by a roller 74 which is movably mounted in a bracket 75 which is permanently attached to the under 90 side of the pressroom floor or to a fixed frame structure. There are ordinarily in practice several of the straps 68 spaced across the length of the roll and it will be understood that they are similarly anchored and secured 95 to the floating roller 74. The web 17 passes over said roller 74, thence downwardly around a roller 76 carried by the lower end of the bracket 75, the course of the web being then upwardly over a guide roller 77 and 100 into the press.

The roller 74 is provided with an upwardly extending arm 78 which carries at its outer end a pin 79 engaging in a slot 81 in the end of a horizontal rod 82 which is pivoted 105 at 83 to a depending lug 84 on the bracket 75, the outer portion of said rod corresponding to the rod 58 as shown in Fig. 1, and having mounted thereon as a counterweight the motor and gear assembly previously described. 110 It will be evident that the tension on the web may be increased by moving said motor outwardly on the rod portion 58 and decreased by moving said assembly inwardly since such movement tends to alter the upward force 115 of the roller 74. While the action is specifically opposite to that in the embodiment of the invention shown in Fig. 1 in the sense that movement of the motor assembly outwardly on the rod tends to increase the tension and inward movement tends to decrease the tension, whereas the reverse action occurs with the construction shown in Fig. 1, the two embodiments are fundamentally similar in that the movement of the motor varies 120 the tension and may be readily controlled by operation of the reversing switch 61. In the embodiment shown in Fig. 3 the tension is to a certain extent automatically controlled in that the web when taut tends to draw the 125

roller 74 downwardly, thus lessening the tension of the straps 68 on the roll and when slack develops in the web said roller 74 is moved upwardly by the weight 59 thus increasing the tension, but in accordance with my invention the tension may be still further controlled to accommodate changing conditions due to such factors as changes in the temperature and humidity affecting the elasticity of the web, the tension mechanism being therefore, more efficient and better adapted to conditions of service than with a construction in which the counterweight or other counter balance for the floating roller is fixed or subject only to manual adjustment.

The foregoing detailed description has been given for clearness of understanding only, and no unnecessary limitations should be understood therefrom, but the appended claims should be construed as broadly as permissible in view of the prior art.

I claim:

1. A web tension device comprising, in combination with a roll support and a machine to which the web is to be supplied; brake mechanism for controlling the roll; means governed by the tension of the web for operating said brake mechanism; a counterweight for regulating said brake operating means; and a remote control device for adjusting said counterweight.

2. A web tension device comprising, in combination with a roll support and a machine to which the web is to be supplied; brake mechanism for controlling the roll; means governed by the tension of the web for operating said brake mechanism; a movable counterbalancing element for regulating said brake operating means; and a remote control device for adjusting the position of said counterbalancing element.

3. A web tension device comprising, in combination with a roll support and a machine to which the web is to be supplied; brake mechanism for controlling the roll; means governed by the tension of the web for operating said brake mechanism; a counterweight comprising a movably mounted motor for regulating said brake operating means; a source of current for said motor; a switch for controlling the supply of current to the motor; and means operable by the motor for adjusting the position of the latter to vary its value as a counterweight, thereby controlling the tension produced by the brake mechanism upon the roll.

4. A web tension device comprising, in combination with a roll support and a machine to which the web is to be supplied; brake mechanism for controlling the roll; means governed by the tension of the web for operating said brake mechanism; a counterweight comprising a movably mounted motor for regulating said brake operating

means; a source of current for said motor; a reversing switch for controlling the supply of current to the motor; and means operable by the motor for adjusting the position of the latter to vary its value as a counterweight, thereby controlling the tension produced by the brake mechanism upon the roll. 70

5. A web tension device comprising, in combination with a roll support and a machine to which the web is to be supplied; 75 brake mechanism for controlling the roll; means governed by the tension of the web for operating said brake mechanism; a counterbalance comprising a movably mounted motor for regulating said brake operating means; a source of current for said motor; a reversing switch located accessibly to the operator of said machine for controlling the supply of current to the motor; and means operable by the motor for adjusting the position of the latter to vary its counterbalancing effect, thereby controlling the tension produced by the brake mechanism upon the roll.

6. A web tension device comprising, in combination with a roll support and a printing press to which the web is to be supplied; 90 brake mechanism for controlling the roll; means governed by the tension of the web for operating said brake mechanism; a counterbalance comprising a movably mounted motor for regulating said brake operating means; a source of current for said motor; a reversing switch located at a control station adjacent the press for controlling the supply and direction of the current to the motor; and means operable by the motor for adjusting the position of the latter to vary the counterbalancing effect thereof, thereby controlling the tension produced by the 100 brake mechanism upon the roll. 95

7. A web tension device comprising, in combination with a roll support and a printing press to which the web is to be supplied; 110 brake mechanism for controlling the roll; means governed by the tension of the web for operating said brake mechanism; a counterbalance comprising a movably mounted motor for regulating said brake operating means; a source of current for said motor; a reversing switch located at a control station adjacent the press for controlling the supply and direction of the current to the motor; and means comprising a threaded 115 rod and an internally threaded motor carriage thereon geared to the motor for adjusting the position of the latter to vary its counterbalancing effect, thereby controlling the tension produced by the brake mechanism upon the roll. 120

8. A web tension device comprising, in combination with a roll support and a printing press to which the web is to be supplied; 125 brake mechanism for controlling the roll; means including a compensating roller gov- 130

- erned by the tension of the web for operating said brake mechanism; a counterbalance for said roller including a rod and a motor mounted thereon, said motor being movable under its own power on said rod; a source of current for said motor; and a reversing switch for controlling the supply of current to said motor.
9. A web tension device comprising, in combination with a roll support and a printing press to which the web is to be supplied; brake mechanism for controlling the roll; means including a compensating roller governed by the tension of the web for operating said brake mechanism; a counterbalance for said roller including a rod and a motor mounted thereon, said motor being movable under its own power on said rod; a source of current for said motor; and a reversing switch located at a control station near the press for controlling the supply of current to the motor.
10. A tension device for web rolls including: means for bringing web rolls, one at a time, into feeding position; controlling mechanism governed by the tension of the web from the roll which is in feeding position, said controlling mechanism including a movably mounted motor operating as a counterweight; and brake mechanism for said rolls to co-act with said controlling mechanism.
11. A tension device for web rolls including: means for bringing web rolls, one at a time, into feeding position; controlling mechanism governed by the tension of the web from the roll which is in feeding position, said controlling mechanism including a counterweight controllable from a remote point to adjust the position thereof; and brake mechanism for said rolls to co-act with said controlling mechanism.
12. A web tension device comprising, in combination with a roll support and a printing press to which the web is to be supplied; brake mechanism for controlling the roll; means including a compensating roller governed by the tension of the web for operating said brake mechanism; and a movably mounted motor controllable from a press control station for counterbalancing said compensating roller to thereby control the tension applied to the roll.

In witness whereof I hereunto subscribe my name to this specification.

ALLAN J. CLINE.
